(57) **CLAIM**

The ornamental design for a fecal specimen collector, as shown and described.

DESCRIPTION

FIG. 1 is a perspective view of a fecal specimen collector, showing a first embodiment of our new design;

FIG. 2 is a front view of FIG. 1;

FIG. 3 is a rear view of FIG. 1;

FIG. 4 is a side view of FIG. 1;

FIG. 5 is an opposite side view of FIG. 1;

FIG. 6 is a top view of FIG. 1;

FIG. 7 is a bottom view of FIG. 1;

FIG. 8 is a sectional view along Lines 8-8 of FIG. 4;

FIG. 9 is an exploded reference view of FIG. 1;

FIG. 10 is a perspective view of a fecal specimen collector, showing a second embodiment of our new design;

FIG. 11 is a front view of FIG. 10;

FIG. 12 is a rear view of FIG. 10;

FIG. 13 is a side view of FIG. 10;

FIG. 14 is an opposite side view of FIG. 10;

FIG. 15 is a top view of FIG. 10;

FIG. 16 is a bottom view of FIG. 10;

FIG. 17 is a sectional view along Lines 17-17 of FIG. 13;

FIG. 18 is an exploded reference view of FIG. 10;

FIG. 19 is a perspective view of a fecal specimen collector, showing a third embodiment of our new design;

FIG. 20 is a front view of FIG. 19;

FIG. 21 is a rear view of FIG. 19;

FIG. 22 is a side view of FIG. 19;

FIG. 23 is an opposite side view of FIG. 19;

FIG. 24 is a top view of FIG. 19;

FIG. 25 is a bottom view of FIG. 19;

FIG. 26 is a sectional view along Lines 26-26 of FIG. 20;

and,

FIG. 27 is an exploded reference view of FIG. 19.
